(57) **CLAIM**

The ornamental design for a capsule nozzle, as shown and described.

DESCRIPTION

FIG. 1 is a perspective view of the capsule nozzle;

FIG. 2 is a front view of the capsule nozzle shown in FIG. 1, the rear view is identical to the front view;

FIG. 3 is a side view of the capsule nozzle shown in FIG. 1, the opposite side view is identical;

FIG. 4 is a top plan view of the capsule nozzle shown in FIG. 1;

FIG. 5 is a bottom plan view of the capsule nozzle shown in FIG. 1;

FIG. 6 is a fragmentary horizontal sectional view taken through the center line of the capsule nozzle shown in FIG. 4; and,

FIG. 7 is a further front view of the capsule nozzle shown in FIG. 1, inserted in a capsule.

The broken line showing portions of the capsule nozzle head and capsule nozzle base are included for the purpose of illustrating unclaimed subject matter and forms no part of the claimed design.

1 Claim, 7 Drawing Sheets
